UNITED STATES PATENT OFFICE.

CHARLES F. SCHNEIDER AND JULIUS HAYMAN, OF WAUKEGAN, ILLINOIS.

WINDOW.

1,073,637.

Specification of Letters Patent. Patented Sept. 23, 1913.

Application filed March 27, 1912. Serial No. 686,593.

To all whom it may concern:

Be it known that we, CHARLES F. SCHNEIDER and JULIUS HAYMAN, citizens of the United States, residing at Waukegan, 5 county of Lake, and State of Illinois, have invented certain new and useful Improvements in Windows, of which the following is a specification.

This invention relates to a novel form of 10 window, which is so constructed that it will permit the proper ventilation of a room without the necessity of a separate, auxiliary ventilating device.

The objects of our invention are to provide 15 a window which is so constructed as to permit fresh air to enter and vitiate or foul air to leave the room without causing undesirable drafts; to provide a combined window and ventilator; and to provide such 20 a construction which will occupy about the same space as an ordinary window and which will be simple and substantial in construction. We accomplish these objects and various other advantages by means of the 25 window shown in the accompanying drawings, in which;

Figure 1 is a front elevation of a window as seen from within a room; Fig. 2 is a cross sectional view with parts broken away, and 30 Fig. 3 is a vertical sectional view on an enlarged scale.

As shown in these drawings, 4 indicates a window frame in which are slidably mounted an upper sash 5 and lower sash 6. 35 These sashes may be counterbalanced by means of any suitable weights, and may be provided with any desired form of catches or locks, such devices being omitted as they form no part of this invention. The lower 40 rail 7 of the bottom sash is preferably made somewhat wider than in ordinary sashes, it being at least sufficiently wide to extend down to the sub-sill 8, while leaving a border of desired width in view above the 45 stool. We provide a strip 9 which extends across the frame adjacent to the lower rail 7, and provide a slide or movable stool 10. This slide or stool is provided with grooves 11, which are adapted to fit over tongues 12, 50 the latter being preferably dadoed into the jambs 13. This slidable member fits closely above the apron 14 and may be partially supported thereby. It is further supported by screws or bolts 15 which engage with the 55 window frame and pass through holes 16 in the stool 10, the outer portions of these

holes being enlarged to receive the heads, thereby providing stops to limit the outer movement of the stool. The outer ends of these holes are preferably plugged as indicated in Fig. 2 to conceal the screw heads. The stool or slide 10 is also provided with a finger grip 17.

In the angle formed between the sub-sill 8 and apron 14 is placed a strip 18, which furnishes an air and water brake and insures a tight joint between these members. The outer face of this strip is beveled and the lower edge thereof is provided with a downwardly extending projection 19 which is dadoed into the sub-sill 8. The opening formed between the cross piece 9 and the apron 14 is preferably provided with a screen 20. This screen may be tacked or otherwise secured to the lower edge of the strip 9 and to the upper edge of the strip 18, as clearly shown in Fig. 3, this forming a convenient means for attachment.

When it is desired to secure the largest amount of ventilation without having a direct opening under the lower sash, it is raised to about the position shown in dotted lines in Fig. 3 and the slide or sill 10 is pulled out to its fullest extent. This provides an opening below the sash and the air can pass in through the screen 20 and will be deflected upwardly so as not to cause an objectionable draft in the room. The opening between the check rail of the bottom sash and the check rail of the top sash will 90 permit the air in the upper part of the room to pass down and out below the top sash, thereby providing ample means for ventilation. On account of the novel construction and arrangement of our window, 95 the air will pass in without blowing the window shade or causing it to flap to any appreciable extent. Furthermore, the window may be left open in this way without any danger of rain, sleet, or the like being 100 driven into the room, as the air is sufficiently deflected so that under ordinary circumstances no moisture would be driven up through the open passage way. The amount of air admitted at the bottom of the window 105 may be regulated by moving the slide or stool 10, so as to increase or decrease the opening. It will also be noted that, on account of the wide bottom rail 7, the stool may be entirely closed and will leave an 110 opening between the check rails, which will permit a certain amount of ventilation. The

air may also be regulated by leaving the slide 10 open and then adjusting the sash 6 so as to increase or decrease the opening underneath the same.

5 When both the sash and stool are closed, it will be seen that a dead air space is formed in the chamber which will prevent annoying or undesirable drafts around the bottom of the window. This is a very desirable feature
10 as a comparatively secure closure will be made even if the lower rail of the sash or the stool are not fitted with the greatest accuracy in their slides.

From the above description and the accompanying drawings it will be readily seen that we provide a combined window and ventilator, or what may be termed a ventilating window, by means of which proper ventilation is secured without requiring any additional attachments or without changing the appearance of the window to any considerable extent. This form of window is not only desirable for houses but for hospitals, vehicles or other places where proper ventilation is desired.

Having thus described our invention which we do not wish to limit to the exact form or arrangement herein shown and described, except as pointed out hereinafter, 30 what we claim and desire to secure by Letters Patent is;

1. A window frame having a chamber in the bottom thereof with openings leading to the outer air and to the inside of a room, 35 a sash having its bottom rail adapted to close the opening to the outer air when the sash is down, and an adjustable stool fitting over the opening leading to the inside of the room and serving to open and close the same.

2. In a window, the combination of a frame, having a sill at the bottom thereof and having an apron engaging with said sill, a sash, a cross piece adjacent to the sash and slightly above the apron, a screen 45 extending between the cross piece and the apron, and a slide mounted above the apron for closing the opening between the apron and the cross piece.

3. A window having a chamber in the bottom of the frame communicating with the outer air and with the inside of a room, the bottom rail of the lower sash of the window serving to close the outer communication when the sash is down, and means for closing 55 the inner communication.

4. A ventilating window having a chamber in the lower part of the frame, the lower rail of the bottom sash forming one side of the chamber when closed, a strip 60 adjacent to the sash at the top of the chamber, said chamber having an opening leading into the room, a screen across said opening and a slidable stool over said opening.

5. In a ventilating window, the combination with the lower sill and apron of a beveled cross piece having a projection dadoed into the sill, a second cross piece adjacent to the sash and above said sill, a screen between said first named cross piece and said 70 second named cross piece, and a slidable stool mounted above the apron and adapted to close the space between the apron and said second named cross piece.

CHARLES F. SCHNEIDER.
JULIUS HAYMAN.
